UNITED STATES PATENT OFFICE

154,201

DESIGN FOR A DRESS

Samuel J. Goldfarb, New York, N. Y.

Application August 22, 1947, Serial No. 140,992

Term of patent 14 years

(Cl. D3—26)

To all whom it may concern:

Be it known that I, Samuel J. Goldfarb, a citizen of the United States, residing at New York, in the county of New York and State of New York, have invented a new, original, and ornamental Design for a Dress, of which the following is a specification, reference being had to the accompanying drawing, forming a part thereof:

In the drawing:

Fig. 1 is a front elevational view of a dress, showing my new design; and

Fig. 2 is a rear elevational view of the same.

I claim:

The ornamental design for a dress, as shown.

SAMUEL J. GOLDFARB.
